CLAIM

The ornamental design for a faucet, as shown and described.

DESCRIPTION

FIG. 1 is a front view of the faucet;
FIG. 2 is a rear view thereof;
FIG. 3 is a right side view thereof;
FIG. 4 is a left side view thereof;
FIG. 5 is a bottom view thereof;
FIG. 6 is a top view thereof;
FIG. 7 is a perspective view thereof;
FIG. 8 is another perspective view thereof;
FIG. 9 is a perspective view thereof, showing a pull-up
spraying-unit of the faucet in an extended position;
FIG. 10 is another perspective view thereof;
FIG. 11 is yet another perspective view thereof; and,
FIG. 12 is still another perspective view thereof.
